(57) **CLAIM**

The ornamental design for an opening tab for a receptacle, as shown and described.

DESCRIPTION

FIG. 1 is an upper perspective view of an opening tab for a receptacle, showing the new design.

FIG. 2 is a lower perspective view thereof.

FIG. 3 is a rear elevational view thereof.

FIG. 4 is a left side elevational view thereof.

FIG. 5 is a right side elevational view thereof.

FIG. 6 is a top plan view thereof;

FIG. 7 is a front elevational view thereof; and,

FIG. 8 is a bottom plan view thereof.

The broken lines shown in the drawings are for illustrative purposes only and form no part of the claimed design. The shading shown in the drawings is only provided to illustrate the contour of the article; it is not indicative of any particular texture.
